UNITED STATES PATENT OFFICE.

GEORGE J. NETH, OF DAYTON, OHIO, ASSIGNOR TO THE EGRY REGISTER COMPANY,
OF DAYTON, OHIO, A CORPORATION OF OHIO.

PAPER-FEEDING DEVICE FOR AUTOGRAPHIC REGISTERS.

Application filed August 4, 1921. Serial No. 439,848.

To all whom it may concern:

Be it known that I, GEORGE J. NETH, a citizen of the United States, residing at Dayton, in the county of Montgomery and State of Ohio, have invented certain new and useful Improvements in Paper-Feeding Devices for Autographic Registers, of which the following is a specification, reference being had therein to the accompanying drawing.

This invention relates to paper feeding devices for autographic registers and the like and more particularly to that type of feeding device in which pin wheels enter rows of perforations in webs of paper to advance the same. In forming the rows of perforations in the webs of paper difficulty is frequently experienced in maintaining the rows of perforations at uniform distances one from the other throughout the length of the web. Where there is a variation in the distance between the rows of perforations and the pin wheels are fixed relatively one to the other, the pins will engage the edges of the perforations and tear the paper, or if the variation is sufficiently great they will leave the perforations entirely, thus interrupting the feeding of the paper and destroying the alignment between the superimposed webs.

It is the object of my invention to provide means for driving or actuating one or more sheets of paper positively and at the same time permit the paper to adjust the position of the driving means in order to accommodate the elements of the driving means to the varying dimensions of the paper due to atmospheric conditions and the like.

It is a further object of my invention to provide such driving means which may be accommodated by the paper according to its lateral dimensions and will hold the paper positively at a predetermined position while the sheets are being worked upon or torn off.

It is a still further object to provide such a holding means accommodating itself to the dimensions of the paper to prevent the paper slipping off of the holding means or tearing the paper and which will also prevent movement of the paper and the driving means therefor in either direction.

One object of the present invention is to provide a feeding device in which the distance between the pin wheels may be auto-

matically adjusted to accommodate the variations in the distances between the rows of perforations in the webs of paper.

A further object of the invention is to provide such a feeding device in which a pin wheel is mounted for free axial movement so that it can follow the perforations in the web.

A further object of the invention is to provide such a device which will be very simple in its construction and operation and which can be constructed and applied to the machine at a low cost.

Another object of the invention is to provide a feeding mechanism with a detent pawl to engage one of the operating gears therefor to hold the same against reverse movement, said pawl being so constructed and arranged that it will operatively engage gears of various diameters without change in the construction or mounting of the pawl, thereby avoiding the necessity of providing a special pawl for each diameter of gear, or of mounting the pawl on an adjustable support so that it can be adjusted to accommodate it to the gears of different diameters.

Other objects of the invention will appear as the device is described in detail.

In the accompanying drawings Fig. 1 is a plan view of a portion of an autographic register, partly broken away to show the feeding mechanism applied thereto; Fig. 2 is a side elevation of a portion of such an autographic register; Fig. 3 is a transverse section taken on the line 3-3 of Fig. 1; Fig. 4 is a longitudinal section taken on the line 4-4 of Fig. 1, looking in the direction of the arrows; Fig. 5 is a section taken on the line 5-5 of Fig. 1, looking in the direction of the arrows; and Fig. 6 is a detail view of the adjustable guide bar.

In these drawings I have illustrated one embodiment of my invention and have shown it as applied to an autographic register of a known construction, but it will be understood that not only may the invention itself take various forms but that it may be applied to autographic registers of various kinds or to other mechanisms embodying a similar feeding device.

In that form of the invention here illustrated the autographic register comprises a main frame, or casing, 1 in which is

mounted a feeding mechanism comprising a shaft 2 journaled in the side walls of the main frame and having mounted thereon pin wheels 3 and 4 adapted to engage rows 5 of perforations 5 formed in actuating elements 6 which are to be advanced by the feeding device. These actuating elements may be of paper or any desired material. The shaft may be rotated in any suitable 10 manner, but, as here shown, it has secured thereto a gear 6 which is connected by means of an idle gear 7 with a driving gear 8 mounted on a shaft 9 journaled in one of the side members of the main frame and 15 having connected therewith a crank or operating handle 10.

The pin wheels 3 and 4 may be of any suitable construction. As here shown they comprise disks mounted on the shaft 2 and 20 each having a circumferential series of pins projecting radially therefrom, the pins being tapered at their outer ends to facilitate their entrance into the perforations in the webs of paper. To enable the pin wheels 25 to accommodate themselves to varying distances between the rows of perforations in the webs they are so mounted that the distance between them will be automatically adjusted according to the variation in the 30 distance between the rows of perforations. This may be accomplished in various ways but in the construction here shown I have mounted one of the pin wheels, the wheel 4, for movement toward and from the other 35 pin wheel, this movement being imparted to the pin wheel by the contact of the pins with the edges of the perforations. Where the two pin wheels are mounted on a common shaft, as here shown, I prefer that one 40 pin wheel should be rigidly secured to the shaft and that the other should be mounted for free sliding, or floating, movement on the shaft, but should be connected thereto in such a manner as to prevent the relative 45 rotation of the pin wheel and the shaft. In the present instance the pin wheel 4 is mounted on the shaft for free sliding movement and is held against rotation relatively thereto by laterally extending pins 11 which 50 are mounted in bearings, or guideways, in a member, such as a cross bar 12, rigidly secured to the shaft. This construction not only prevents relative rotation of the shaft and the pin wheel but prevents any tilting 55 movement on the part of the pin wheel and retains the same in a plane at right angles to the axis of the shaft. It will be apparent, therefore, that if the distance between the rows of perforations 5 and the webs of 60 paper vary the contact of the pins of the pin wheel 4 with the edges of the perforations will impart lateral movement to the pin wheel on the driving shaft, thus maintaining the pin wheel always in line with 65 the row of perforations. While, of course,

the second pin wheel may, if desired, be adjustably mounted this is not necessary as the web of paper will shift laterally sufficiently to maintain the row of perforations in line with the pins of this second pin 70 wheel, this lateral shifting of the web being permitted by the movement of the laterally movable pin wheel.

It is customary in pin wheel feeding devices to provide the top plate of the machine which extends above the pin wheels, as shown at 13, with a slotted guide bar, as shown at 14 in Figs. 3 and 5, these guide bars being so arranged that they will engage the uppermost web of paper and hold 80 the same below the outer ends of the uppermost pins of the pin wheel, thereby causing the pins to project through the openings and maintaining a firm operative connection between the pin wheels and the web. 85 Where the pin wheels are fixed against axial movement the guide bars are rigidly secured to, or formed integral with, the top plate 13, as shown at 14. When the pin wheel is mounted for axial adjustment it is preferable that the guide bar should also be adjustable. I have, therefore, shown the guide bar for the adjustable pin wheel as formed separately from the top plate, as shown at 15, and pivotally mounted thereon at a point removed a considerable distance from the pin wheel so that the movement of the bar about its axis will not cause the slot to be placed at such an angle to the pin wheel as to interfere with its rotation. 90 I also prefer to extend the bar some distance beyond its pivot, as shown at 16, so as to form a brace which will prevent the forward, or slotted, end of the bar from sagging or dropping away from the top plate. 100 It will be apparent that inasmuch as the pins project into the slot of the bar 15 that the axial movement of the pin wheel will also impart movement to the bar, thus maintaining the slotted portion thereof at all 110 times in operative relation to the pin wheel. 115 A detent, or pawl, is usually applied to one of the gears, preferably the gear 8, of the feeding mechanism to prevent the reverse movement of the feeding mechanism. In different machines, or machines of different capacities, the diameter of the gear 8 will vary and to avoid the use of a different pawl for each diameter of gear, it has been customary to so mount the pawl 120 on the main frame of the register that it can be adjusted to accommodate it to gears of different diameters. To accomplish this, however, requires a more or less complicated construction consisting of a number of parts 125 and also requires that a careful adjustment should be made in the assembling of the machine. In the present invention I have provided a single pawl which is so constructed and arranged that it can be mounted at the 130

same point on the side wall of any register and will operatively engage the gear regardless of the diameter of the latter, thereby enabling a single part to be used where 5 formerly several parts were required and eliminating all adjustment, which results in a material saving in manufacturing and assembling costs, as well as preventing the possibility of the pawl being improperly adjusted or of the adjustable support slipping so as to render the pawl inoperative. As here shown, this pawl consists of an elongated body 17 pivotally mounted at 18 and having its outer end curved to extend about 10 the gear and provided with a tooth or nose 19 to engage the teeth of the gear, the arrangement of the pawl being such that the tooth will engage one of the uppermost teeth in the gear. The intermediate portion of the pawl is increased in width, as shown at 20, to provide sufficient weight 15 to hold the same in operative engagement with the gear, thereby eliminating the use of springs. It will be noted that the arrangement of the pawl is such that it moves 20 substantially radially of the gear and that it will occupy an operative position to the gear regardless of the diameter of the latter.

25 While I have shown and described one embodiment of my invention I wish it to be understood that I do not desire to be limited to the details thereof as various modifications may occur to a person skilled 30 in the art.

Having now fully described my invention, what I claim as new and desire to secure by Letters Patent, is:

1. In an autographic register adapted to 40 contain a plurality of sheets having perforated margins with perforations of uniform size, pin wheel feeding devices always engaging with the sheets entering the perforations in the margins of the paper, means 45 to actuate said pin wheel devices and means to permit said pin wheel to move laterally on its actuating means.

2. In an autographic register containing 50 a plurality of sheets of paper having marginal perforations, a pin wheel to actuate said paper always engaging with the sheets, means to actuate said pin wheel and means to permit of the lateral movement of the pin wheel on the actuating means but adapted 55 to cause it to turn with the actuating means, the lateral movement being imparted to the pin wheel by the paper in contact with the pin wheel, the pin wheel in turn imparting forward movement to the paper.

60 3. In an autographic register, an actuating element adapted to move laterally a feeding pin wheel engaging with perforations in the actuating element, a pin wheel, a means for actuating the pin wheel turning 65 with the pin wheel, but moving lateral-

ly on the actuating means and means to permit and guide the lateral movement of the pin wheel.

4. In an autographic register a feeding device consisting of an actuating means 70 and a pin wheel thereon, said pin wheel being mounted on the actuating means, means on said actuating means to guide said pin wheel in lateral movement thereon, a plurality of superimposed actuating elements 75 having a series of perforations therein for engaging with the pins on the pin wheel whereby lateral movement of the pin wheel is imparted by the actuating elements and forward movement is imparted to the actuating elements by the actuating means operating through the pin wheel.

5. In an autographic register, a pin wheel a driving shaft for said pin wheel, means 85 on the shaft for guiding the pin wheels in lateral movement thereon, said means consisting of a member fixed to said shaft having guide ways therein, and laterally projecting pins on said pin wheel traveling freely on said guide ways.

6. In an autographic register adapted to contain paper having marginal perforations, actuating pin wheels engaging in the perforations in the paper, a driving means having thereon means for rotating one of said pin 90 wheels while permitting it to move laterally thereon to accommodate the varying width of paper between the rows of the perforations, the pin wheels being moved laterally by the contact of the sides of the perforations with the sides of the pins and the paper being moved forwardly by the contact of the pins with the walls of the perforations.

7. In an autographic register adapted to contain paper having marginal perforations, 105 actuating pin wheels located in said register engaging in the perforations in the paper, a driving means having thereon means for rotating one of said pin wheels while permitting it to move laterally thereon to accommodate the varying width of the paper between the rows of the perforations, the pin wheel being moved laterally by the contact of the sides of the perforations with the sides of the pins and the paper being moved forwardly by the contact of the pins with the walls of the perforations, and means on the driving means to prevent it from movement at a predetermined point.

8. In an autographic register adapted to contain paper having marginal perforations, actuating pin wheels located in said register engaging on the perforations in the paper, a driving means having thereon means for rotating one of said pin wheels while permitting it to move laterally thereon to accommodate the varying width of paper between the rows of the perforations, the pin wheel being moved laterally by the contact 115 of the sides of the perforations with the sides of the pins and the paper being moved forwardly by the contact of the pins with the walls of the perforations, and means on the driving means to prevent it from movement at a predetermined point.

sides of the pins and the paper being moved forwardly by the contact of the pins with the walls of the perforations, and means on the driving means to prevent it from movement at a predetermined point to prevent the backward movement of the pin wheel actuating means.

9. In an autographic register adapted to contain paper having marginal perforations, 10 actuating pin wheels located in said register engaging in the perforations in the paper, a driving means having thereon means for rotating one of said pin wheels while permitting it to move laterally thereon to accommodate the varying width of paper between the rows of the perforations, the pin wheel being moved laterally by the contact of the sides of the perforations with the sides of the pins and the paper being moved 20 forwardly by the contact of the pin wheel with the walls of the perforations, and means on the driving means to prevent it from movement at a predetermined point to prevent the backward movement of the pin wheel actuating means, said last mentioned means being adjustable to varying sizes of driving gearing associated with the actuating means.

10. In an autographic register, an actuating means, a pin wheel turning with the actuating means and means associating with and adjacent to the pin wheels for maintaining a perforated element in engagement with said pin wheels, means to permit the 35 lateral movement of the pin wheel on the actuating means and means to permit the cooperating lateral movement of the means retaining the perforated element on the pin wheels, whereby the retaining element and the pin wheel move laterally together.

11. In an autographic register, an actuating means, a pin wheel turning with the actuating means, and means associating with and adjacent to the pin wheels for maintaining a perforated element in engagement with said pin wheels, means to permit lateral movement of the pin wheel on the actuating means and means to permit the cooperating lateral movement of the means retaining the perforated element on the pin wheels, whereby the retaining element and the pin wheel move laterally together, and means on the retaining element to maintain it in the same horizontal plane as it swings from side to side.

12. In an autographic register, an actuating shaft and pin wheel being mounted on said shaft on one end thereof, a second pin wheel mounted on the shaft adjacent the other end thereof, turning with the shaft and capable of lateral movement thereon, means to guide the second pin wheel in its lateral movement relative to the shaft, a plurality of perforated elements having marginal perforations in engagement with the

pins on pin wheels, said elements moving laterally the transversely moving pin wheel to accommodate varying distances between the marginal rows of perforations.

13. In an autographic register, an actuating shaft and pin wheel being mounted on said shaft on one end thereof, a second pin wheel mounted on the shaft adjacent the other end thereof, turning with the shaft and capable of lateral movement thereon, 70 means to guide the second pin wheel in its lateral movement relative to the shaft, a plurality of perforated elements having marginal perforations in engagement with the pins on pin wheels, said elements moving laterally the transversely moving pin wheels to accommodate varying distances between the marginal rows of perforations and retaining members to retain the perforated elements on the pins of the pin wheel without the lateral movement and on the transversely moving pin wheel.

14. In an autographic register, an actuating shaft and pin wheel being mounted on said shaft on one end thereof, a second 90 pin wheel mounted on the shaft adjacent the other end thereof, turning with the shaft and capable of lateral movement thereon means to guide the second pin wheel in its lateral movement relative to the shaft, a plurality of perforated elements having marginal perforations in engagement with the pin on pin wheels, said elements moving laterally the transversely moving pin wheel to accommodate varying distances between the marginal rows of perforations and retaining members to retain the perforated elements on the pins of the pin wheel without the lateral movement and on the transversely moving pin wheel, said register having a cover with said retaining elements on the under side thereof.

15. In an autographic register, an actuating shaft and pin wheel being mounted on said shaft on one end thereof, a second pin wheel mounted on the shaft adjacent the other end thereof, turning with the shaft and capable of lateral movement thereon means to guide the second pin wheel in its lateral movement relative to the shaft, a plurality of perforated elements engaging with the pin wheels, whereby said elements are adapted to move laterally the transversely moving pin wheel to accommodate varying distances between the marginal rows of perforations, and retaining members to retain the perforated elements on the pin wheel without the lateral movement and on the transversely moving pin wheel, said register having a cover with said retaining element on the under side thereof, and means for maintaining said pin wheels from forward movement when desired.

16. In an autographic register, an actuating shaft and pin wheel mounted on said

shaft on one end thereof, a second pin wheel mounted on the shaft adjacent the other end thereof, turning with the shaft and capable of lateral movement thereon means to guide the second pin wheel in its lateral movement relative to the shaft, a plurality of perforated elements having marginal perforations in engagement with the pins on the pin wheels, said elements moving laterally the transversely moving pin wheel to accommodate varying distances between the marginal rows of perforations and retaining

members to retain the perforated elements on the pins of the pin wheel without the lateral movement and on the transversely moving pin wheel, said register having a cover with said retaining element on the under side thereof, means for maintaining said pin wheels from forward movement when desired, and means for maintaining said pin wheels from backward movement.

In testimony whereof, I affix my signature hereto.

GEORGE J. NETH.
